UNITED STATES PATENT OFFICE.

MAXIMILLIAN NEUMAYER, OF CINCINNATI, OHIO; CLARA NEUMAYER ADMINISTRATRIX OF SAID MAXIMILLIAN NEUMAYER, DECEASED.

CENTRIFUGAL PUMP OR BLOWER.

1,029,554.

Specification of Letters Patent. Patented June 11, 1912.

Application filed July 24, 1908. Serial No. 445,109.

To all whom it may concern:

Be it known that I, MAXIMILLIAN NEUMAYER, a subject of the King of Hungary, and a resident of Cincinnati, in the county 5 of Hamilton and State of Ohio, have invented a new and Improved Centrifugal Pump or Blower, of which the following is a full, clear, and exact description.

The object of the invention is to provide 10 a new and improved centrifugal pump, blower or similar machine, which is simple and durable in construction, rendered very effective in operation by the use of a special runner and a plurality of suction chambers, 15 so that the fluid passes through the machine in stages with increasing velocity, the fluid finally leaving the machine under a desired pressure and predetermined delivery capacity.

20 The invention consists of novel features and parts and combinations of the same, which will be more fully described herein-after and then pointed out in the claims.

A practical embodiment of the invention 25 is represented in the accompanying drawings forming a part of this specification, in which similar characters of reference indicate corresponding parts in all the views.

30 Figure 1 is a side elevation of the improvement with the contracted inlet nozzle removed, and arranged as a two-stage blower; Fig. 2 is a transverse section of the same on the line 2—2 of Fig. 1; Fig. 35 3 is a like view of the same, arranged as a three-stage blower; Fig. 4 is a similar view of the same, arranged as a three-stage double intake blower; Fig. 5 is a side elevation of the improvement, arranged as a 40 pump; Fig. 6 is a transverse section of the same on the line 6—6 of Fig. 5; Fig. 7 is a diagrammatic view of the two-stage machine; Fig. 8 is a like view of the three-stage machine; Fig. 9 is an enlarged face 45 view of one of the blades for the two-stage machine; Fig. 10 is a sectional side elevation of the same on the line 10—10 of Fig. 9; Fig. 11 is an enlarged face view of one of the blades for a three-stage machine; Fig. 12 is a sectional side elevation of the same on the line 12—12 of Fig. 11; Fig. 50 13 is a face view of one of the reinforced blades for a two-stage machine; and Fig. 14 is a sectional side elevation of the same 55 on the line 14—14 of Fig. 13.

The casing A of the blower or fan illustrated in Figs. 1, 2, 3 and 4, is preferably of spiral shape, and in it is mounted to turn the runner B, secured on a shaft C extending through one side of the casing 60 and journaled at its outer end in a suitable bearing D, the shaft being connected at the outer terminal by a pulley E, or other means, with other machinery, for imparting a rotary motion to the shaft C and consequently to the runner B. A contracted inlet nozzle F opens into the first suction chamber G, centrally arranged in the runner B, so that the air or other fluid is drawn in by the runner B through the contracted 70 inlet nozzle F and is given a predetermined velocity by the runner and is finally forced out through the outlet H of the casing A, as hereinafter more fully explained.

The runner B is constructed in detail as 75 follows: The frame of the runner consists of an outer ring B' and a disk B² attached to the shaft C, and to the opposite faces of the ring B' and the outer end of the disk B² are bolted or otherwise secured the flanges 80 B³, rigidly connected with each other by blades B⁴, B⁵, of which the blades B⁴ are curved outwardly and rearwardly while the blades B⁵ are curved outwardly and forwardly, considering that the runner B is 85 rotating in the direction of the arrow a'. The adjacent ends of the blades B⁴, B⁵ are spaced apart so as to form an annular second suction chamber G', and the blades B⁴ form an inner set of blades while the 90 blades B⁵ form an outer set of blades, and the blades B⁴ alternate with the blades B⁵, as will be readily understood by reference to Figs. 1, 7, 9, 10, 13 and 14.

When the runner B is rotated, air or 95 other fluid is drawn through the contracted nozzle F into the first suction chamber G, and then the fluid is scooped up by the innermost sets of blades B⁴ and delivered by the same to the second suction chamber G', 100 in which the fluid is scooped up by the outer set of blades B⁵, and delivered into the casing A, from which the fluid passes by the outlet H to its place of discharge. By reference to the parallelograms of forces 105 shown in Fig. 7, the blades B⁴ take up the fluid in the first suction chamber G at a peripheral velocity and deliver the fluid to the second suction chamber G' at an increased velocity, and the blades B⁵ take up the fluid 110

from the second suction chamber G' and deliver it at their outer ends at a further increased velocity, so that the fluid finally leaves the casing A at the outlet H at a 5 very high velocity.

If desired, the runner B may be provided with more suction chambers, and for this purpose intermediate blades B^s are used, as shown in Figs. 3, 4, 8, 11 and 12, the blades 10 B^s being interposed between the sets of innermost and outermost blades B^4 and B^5 , and the blades B^s are slightly curved forwardly and outwardly and spaced from the blades B^4 to form the second suction chamber G' , and spaced from the blades B^5 to form a third suction chamber G^2 . Thus 15 when the runner B is rotating, the blades B^4 scoop up the fluid from the first suction chamber G , and deliver it to the second suction chamber G' , from which the fluid is 20 passed by the intermediate blades B^s into the annular third suction chamber G^2 , from which the fluid is taken up by the blades B^5 and delivered into the outer portion of the 25 casing A and to the outlet H . As indicated in Figs. 11 and 12, the corresponding blades B^4 , B^5 , B^s are integrally connected with the flanges B^8 , fastened by bolts or other means to the ring B' and the disk B^2 . The inner 30 or adjacent ends of the blades B^4 , B^5 may be strengthened by connecting ribs B^7 , as indicated in Figs. 13 and 14.

As shown in Fig. 4, the casing A is provided on opposite sides with contracted intake nozzles F' , F^2 , and in this case the runner B has its frame formed of outer rings B^8 , B^9 and its central disk B^{10} secured to the shaft C , journaled at both outer ends in bearings D' . The rings B^8 , B^9 are connected with the disk B^{10} by the blades B^4 , B^5 , the same as shown in Figs. 1 and 2, or by the blades B^4 , B^5 , B^s , as indicated in 40 Fig. 3, it being understood in this case that a double intake and a double runner are 45 provided.

From the foregoing it will be seen that by the arrangement described, the fluid is acted on in successive stages in the suction chambers G , G' , G^2 , so as to increase the velocity 50 of the fluid, it being understood that the suction chambers G' , G^2 are preferably of varying sizes relatively one to the other; that is, for medium pressure and high delivery capacity, the third suction chamber 55 G^2 is larger than the second suction chamber G' , but for high pressure machines, the capacity of the third suction chamber is preferably equal to or smaller than the capacity of the second suction chamber G' .

As shown in Figs. 5 and 6, the casing A' 60 of the centrifugal pump is provided at one face with a suction pipe F^s , and in the casing A' rotates the runner B of the two-blade or three-blade design, the same as 65 shown and described above in reference to

Figs. 2 and 3. When the runner B of the pump is rotating a suction is created in the first suction chamber G , whereby the liquid is drawn up the suction pipe F^s into the first suction chamber G , in which the liquid is scooped up by the blades B^4 and delivered by the latter to the second suction chamber G' , to be then taken up by the blades B^5 and delivered to the casing A' and the delivery or outlet H' . If a runner B having three sets of blades is used in the pump, then the liquid is passed successively from the first suction chamber G to the second suction chamber G' , then to the third suction chamber G^2 and finally into the outer portion of 70 the casing A' and to the delivery H' . 75

In practice, I prefer to attach the sets of blades B^4 and B^5 or B^4 , B^5 , B^s on corresponding flanges B^8 , which in turn are bolted to the ring B' and the disk B^2 , but, 80 if desired, the blades B^4 , B^5 , B^s may be fastened in position on the frame of the runner. 85

Having thus described my invention, I claim as new and desire to secure by Letters 90 Patent:

1. A centrifugal pump, blower or like machine, provided with a runner having a single inlet, and a plurality of annular concentric suction chambers entirely within the 95 runner and moving therewith.

2. A centrifugal pump, blower or like machine, having a runner provided with a plurality of concentric suction chambers, of varying capacity entirely within the runner 100 and traveling therewith.

3. A centrifugal pump, blower or like machine, comprising a casing, a runner entirely therein having a plurality of concentric suction chambers within the runner and 105 traveling therewith, and a series of blades in each chamber.

4. A centrifugal pump, blower or like machine, comprising a casing and a runner, the casing having an inlet and an outlet, 110 and the runner having a series of blades, and a plurality of series of suction chambers, the suction chambers alternating with the series of blades, said chambers being entirely within and traveling with the runners. 115

5. A centrifugal pump, blower or like machine, comprising a casing and a runner, the casing having an inlet and an outlet, and the runner having a central suction chamber, an annular series of blades encircling 120 the central suction chamber, one of said series being spaced radially with respect to the other series, whereby to form a suction chamber between the series and concentric with the central suction chamber. 125

6. A centrifugal pump, blower or like machine, comprising a casing, a runner therein having a plurality of suction chambers entirely within the runner and traveling therewith, and a plurality of series of 130

- blades, the series of blades alternating with the suction chambers, the blades of one series being curved in one direction and the blades of the other series in the opposite direction. 5
7. A centrifugal pump, blower or like machine, comprising a casing and a runner, the casing having an inlet and an outlet, and the runner having annular series of 10 blades, the series being spaced apart radially to form an annular suction chamber within the runner. 10
8. A centrifugal pump, blower or like machine, comprising a casing and a runner, the casing having an inlet and an outlet, and the runner having annular series of 15 blades, the series being spaced apart radially to form a plurality of annular suction chambers within the runner. 15
9. A centrifugal pump, blower or like machine, comprising a casing and a runner, the casing having an inlet and an outlet, and the runner having annular series of 20 blades, the series being spaced apart radially to form a plurality of annular suction chambers within the runner of varying capacity. 20
10. A centrifugal pump, blower or like machine, comprising a casing and a runner, the casing having an inlet and an outlet, and the runner having annular series of 25 blades, the blades of one series extending in an opposite direction to the blades of the other series, the series being spaced apart 30 radially to form an annular suction chamber within the runner. 30
11. A centrifugal pump, blower or like machine, comprising a casing and a runner, the casing having an inlet and an outlet, and the runner having suction chambers therein having annular series of blades, the series being spaced apart radially to form a suction chamber between each series, the blades of the inner series being curved backward 35 and outward, and the blades in the outer series being curved forward and outward in the direction in which the runner is running. 45
12. A centrifugal pump, blower or like machine, comprising a casing and a runner, the casing having an inlet and an outlet, and the runner having suction chambers and annular series of blades, the series being spaced apart radially to form a suction 50 chamber between each series, the blades of the inner series being curved backward and outward and the blades in the outer series being curved forward and outward in the direction in which the runner is running, 55 the inner series of blades surrounding a first suction chamber, and the series being spaced apart to form an annular second suction chamber. 60
13. A centrifugal pump, blower or like machine, comprising a casing and a runner, 65
- the casing having an inlet and an outlet, the runner having suction chambers and annular series of inner, outer and intermediate blades, the series being spaced apart radially, the blades alternating with the chambers of the inner series being curved backward and outward, the blades in the outer series being curved forward and outward in the direction in which the runner is running, and the blades in the intermediate series being slightly curved forward and outward. 70
14. A centrifugal pump, blower or like machine, comprising a casing and a runner, the casing having an inlet and an outlet, and the runner having suction chambers and 80 annular series of inner, outer and intermediate blades alternating with the chambers, the blades of the inner series being curved backward and outward, the blades in the outer series being curved forward and outward in the direction in which the runner is running, and the blades in the intermediate series being slightly curved forward and outward, the series of blades being spaced apart to form annular concentric suction 85 chambers. 90
15. A centrifugal pump, blower or like machine, comprising a casing and a runner, the casing having an inlet and an outlet, and the runner having suction chambers and annular series of blades alternating with the chambers, the blades of the inner series being curved backward and outward and inclosing a first suction chamber, the blades in the outer series being curved forward 95 and outward in the direction in which the runner is running, and the blades of the intermediate series being slightly curved forward and outward, the series of blades being spaced apart to form annular concentric suction 100 chambers. 105
16. A centrifugal pump, blower or like machine, provided with a runner having blades arranged in concentric annular series, the blades of one series alternating with the 110 blades of the other series and the series being spaced apart radially to form an annular suction chamber within the runner and traveling therewith. 110
17. A centrifugal pump, blower or like machine, provided with a runner having blades arranged in concentric series, the blades of one series alternating with the blades of the other series, the series being spaced apart to form an annular suction 115 chamber within the runner and traveling therewith, and the blades of the innermost series being curved rearward and outward and the blades of the outer series being curved forward and outward. 120
18. A centrifugal pump, blower or like machine, provided with a runner having blades arranged in concentric series, the blades of one series alternating with the blades of the other series and the series 125 130

4

being spaced apart to form an annular suction chamber, the blades of the innermost series being curved rearward and outward and the blades of the outer series being curved forward and outward, a pair of adjacent inner and outer blades being integrally connected, and a runner frame on which the said pair of blades are secured.

19. A centrifugal pump, blower or like machine, provided with a runner having blades arranged in concentric series, the blades of one series alternating with the blades of the other series and the series being spaced apart to form an annular suction chamber, the blades of the innermost series being curved rearward and outward and the blades of the outer series being curved forward and outward, attaching curved flanges integrally connecting the ends of a pair of adjacent inner and outer blades with each other, and a ring frame on which the said flanges are secured.

20. A centrifugal pump, blower or like machine, having a rotor provided with suction chambers entirely within and inclosed by the rotor, and traveling with the rotor during its rotation, and a series of blades in each chamber. 25

21. A centrifugal pump blower or like machine, comprising a casing, a runner within the casing and provided with suction chambers entirely within and inclosed by the runner and traveling therewith during its rotation, said runner having a single inlet, and a series of blades in each of the said 30 35 chambers.

In testimony whereof I have signed my name to this specification in the presence of two subscribing witnesses.

MAXIMILLIAN NEUMAYER.
